UNITED STATES PATENT OFFICE.

CHARLES RAYBUCK, OF SPRANKLE MILLS, PENNSYLVANIA.

GRINDING-MACHINE.

1,056,940.

Patented Mar. 25, 1913.

Application filed June 11, 1912. Serial No. 703,022.

To all whom it may concern:

Be it known that I, CHARLES RAYBUCK, a citizen of the United States, residing at Sprankle Mills, in the county of Jefferson 5 and State of Pennsylvania, have invented certain new and useful Improvements in Grinding-Machines, of which the following is a specification.

My invention relates to grinding machines for grinding the cutter blades of mowing machines, for sharpening disk plows, disk harrows, and disk drills, while in place on the machines, sharpening horse shoe calks while the shoes are on the hoof, 10 smoothing floors, and the like, and has for its object the provision of a grinding mechanism adapted to be secured to a flexible shaft; the invention lying principally in the construction of the hand hold for operating 15 the tool.

My invention will be described in detail hereinafter and illustrated in the accompanying drawings, in which—

Figure 1 is a view in elevation of my improved grinding machine, showing it applied to the fragment of a flexible shaft; Fig. 2, a longitudinal sectional view, and Fig. 3, a cross section through the bearing casing.

In the drawings similar reference characters will be used to designate corresponding parts in the several views.

My improved grinding machine is adapted to be secured to a flexible shaft indicated 35 at A in the drawings, said shaft being such as is ordinarily employed with the well known hair clipping machines used for animal shearing. Secured to the terminal 40 of shaft A is a bar 1 having its free terminal threaded as shown at 1^a.

2 indicates a cup-shaped casing having a concentric threaded socket 2^a to receive the threaded end 1^a of the bar 1, the rear portion of the casing being provided with a lateral shoulder 3, and a reduced and threaded portion 4.

5 indicates a disk of abrasive material mounted on reduced portion 4 and provided with a socket 5^a to receive a washer 6 mounted on said reduced portion 4 and a nut 7 secured thereon. The construction of the disk 5 with the socket 5^a, as described, is preferred when the grinding disk is used for smoothing floors, and the like, and the end 55 of the disk is employed in the operation, but

may be dispensed with if it be desired without altering the spirit of my invention.

The cup-shaped casing 2 is formed with a circular flange 8, and an annular flange 9 integral therewith and surrounding the end 60 of bar 1 and open toward the shaft A. Mounted on the bar 1 is a rotatable sleeve 10, having its terminal within the annular flange 9 enlarged as shown at 11 to snugly fit the interior thereof and to rotate therein. 65 The periphery of the enlargement 11 is formed with a ball raceway 12, and the interior of the flange 9 with a raceway 13 opposite thereto.

14 indicates anti-friction bearings mounted in the raceways 12 and 13. The outer face of the enlargement 11 is also formed with an annular raceway 15 and the circular flange 8 with a raceway 16 opposite to and corresponding with said raceway 15. 75 17 indicates anti-friction bearings mounted in raceways 15 and 16.

In use it will be understood that my improved grinding machine is held by the sleeve 10 while in operative position, and 80 anti-frictional bearings 14 and 17 relieving the friction rotatorily and the thrust, the machine being adapted for grinding either on the periphery of the disk or its outer surface as desired, and by the peculiar construction thereof and its adaptability to be secured to a flexible shaft, provision is made 85 for grinding edge tools while in place in their mountings, such as the cutter blades on the sickle bars of mowing machines, 90 horseshoe calks on the animal's hoofs, and the like.

For the purpose of assembling and dismembering the bar and sleeve I provide the flange 9 with a threaded opening 18 through 95 which the bearing members 14 may be removed and replaced, and close said opening by means of a threaded plug 19 having its inner terminal formed with a semicircular groove 20 that forms a part of the raceway 100 13 when in position. In dismembering the sleeve 10 and bar 1 the plug 19 is removed from the opening 18 and the bearing members 14 dumped from the casing there-through. The sleeve may then be removed 105 from the casing and the bearing members 17 also removed therefrom. In replacing the sleeve the bearing members 17 are first placed in the raceway 16 in the casing when the bar 1 is in an upright position. The 110

sleeve 10 is then placed on the bar and lowered into position so that the enlargement 11 is within the casing. The bar is then turned on its side with the opening 18 uppermost and the bearing members 14 inserted through the opening into the raceways, 12 and 13. The plug 19 is then screwed into position, and the device is in position for use.

Having thus described my invention what 10 I claim is:

1. A grinding machine comprising, in combination with a flexible shaft, a bar secured to one terminal of said shaft, a grinding implement secured to said bar, a bearing 15 casing secured to said bar, a sleeve rotatably mounted on the bar, and an enlargement on one terminal of said sleeve and rotatably mounted in said casing.
2. A grinding machine comprising, in 20 combination with a flexible shaft, a bar secured to said shaft, a grinding implement

secured to the bar, a laterally extending flange or web formed integral with or rigidly secured to said bar; an annular casing formed integral with or rigidly secured to 25 said web or flange, the inner surface of said casing and said flange or web being provided with raceway rings, a sleeve rotatably mounted on said bar, said sleeve having an enlarged head on one of its terminals and 30 adapted to fit within the casing aforesaid, said enlarged head being formed with raceway rings corresponding with the first mentioned raceway rings, and antifrictional bearing members mounted in said raceway 35 rings.

In testimony whereof I affix my signature in presence of two witnesses.

CHARLES RAYBUCK.
